UNITED STATES PATENT OFFICE.

TALBOT C. DEXTER, OF PEARL RIVER, NEW YORK, ASSIGNOR TO THE DEXTER FOLDER COMPANY, OF NEW YORK, N. Y.

PAPER-REGISTERING INSTRUMENT.

SPECIFICATION forming part of Letters Patent No. 655,962, dated August 14, 1900.

Application filed May 29, 1899. Serial No. 718,655. (No model.)

To all whom it may concern:

Be it known that I, TALBOT C. DEXTER, a citizen of the United States, and a resident of Pearl River, in the county of Rockland, in the State of New York, have invented new and useful Improvements in Paper - Registering Instruments, of which the following, taken in connection with the accompanying drawings, is a full, clear, and exact description.

10 This invention pertains to registering instruments employed chiefly on paper-folding machines for the purpose of automatically registering or alining the paper preparatory to being folded, and the invention has special reference to the class of automatic registering instruments which are usually designated "point-feed" registering, and which effect the said registering by engaging a slit or perforation made in the paper for that purpose.

The object of the invention is to provide a registering instrument which shall be simple in construction, efficient in operation, and adapted to be employed on a paper-folding machine in which the folding-rollers are disposed parallel with the paper-delivering tapes or in which the paper is moved laterally after it has been alined by the registering instrument and which instrument shall permit said lateral movement without danger of tearing the paper or throwing it out of alinement or register; and to that end the invention consists, mainly, of a registering instrument normally disposed to register the paper traversing said instrument and sustained yieldingly to the subsequent draft of the paper laterally from its aforesaid movement; and the invention also consists in certain novel features of the details of its construction and auxiliary 40 devices connected therewith, as hereinafter described and claimed.

In the accompanying drawings, Figure 1 is a plan view of a paper - folding machine equipped with my improved paper-registering instrument. Fig. 2 is a vertical longitudinal section on line Y Y in Fig. 1. Fig. 3 is an enlarged vertical longitudinal section on line X X in Fig. 1. Fig. 4 is an enlarged vertical longitudinal section of the lower portion of the bracket provided with one of the pivots which support the registering instru-

ment proper. Fig. 5 is an enlarged plan view of the registering instrument with the slit-opening bridge used in connection therewith. Fig. 6 is a plan view taken immediately beneath the registering instrument. Fig. 7 is a vertical transverse section on line Z Z in Fig. 6; and Figs. 8 and 9 are enlarged rear and side views, respectively, of the registering-point.

Similar letters of reference indicate corresponding parts.

A represents the main supporting-frame of a paper-folding machine. B B are the paper-folding rollers. C is the blade which introduces the paper into the bite of the aforesaid rollers. a a are the paper-conveying tapes which deliver the paper over the folding-rollers, and D denotes the front stop or end gage which arrests the movement of the paper on the aforesaid tapes. All of said parts operate in the usual and well-known manner.

My present invention is designed for registering paper on paper-folding machines in which the folding-rollers B B are arranged parallel with the tapes a a, as shown in Fig. 1 of the drawings, or on other machines having paper-conveyers delivering the paper in one direction on said machine and means for removing the delivered paper from said conveyors laterally or at right angles from the aforesaid direction.

The purpose of the invention is to register the paper on the tapes or conveyors and to allow the paper to be subsequently drawn laterally or at right angles from said tapes or conveyors without causing the registering instrument to either injure the paper or throw it out of register or alinement, as hereinbefore stated.

My present invention is susceptible of modifications of its details. The essential feature, however, is a suitable support which allows the registering instrument to yield laterally from its registering position, as aforesaid. For this purpose I prefer to pivot the registering instrument to its support in such a manner as to allow it to swing toward and from the folding-rollers B B and provide said support with a suitable stop to arrest the swinging movement of the registering instrument at its registering position and means

for normally holding said instrument in contact with said stop. My present invention shows said feature embodied in the following structure of the instrument and auxiliary devices employed in connection therewith.

5 A rock-shaft F extends across the machine and is mounted in bearings on posts E, secured to the sides of the frame A. A lever F' is fastened to the end of said shaft and 10 has its free end held in contact with a rotary cam F², which imparts intermittently-oscillatory motion to said lever.

Over opposite sides of the folding-blade C are rock-arms b b, which are adjustably secured to the rock-shaft to allow said arms to 15 be adjusted so as to carry the registering instrument in proper positions to engage the registering slits or perforations in the paper.

The registering instruments are carried on 20 the free ends of the rock-arms b b, and in order to allow said instruments to be carried a greater or less distance from the rock-shaft, according to the distance of the aforesaid slits or perforations from the advance edge 25 of the paper, I make each of the arms b adjustable in length preferably by forming said arm of two end sections spliced together by means of a sleeve c, embracing the adjacent end portions of said sections and adjustably 30 clamped thereon by set-screws c' c'. The free end of the arm b is formed with a bracket consisting of a longitudinal extension b' of the arm and a branch d extending, preferably, upward from said extension. Said extension 35 and branch are provided with screw-threaded eyes d' d', which are axially in line with each other. In said eyes are inserted vertically-adjustable screws d², formed at their adjacent ends with pivot-points which sustain be- 40 tween them a hub e' of an arm e, extending downward and approximately to the plane of the tapes a a and constituting the registering instrument proper. Said instrument is thus pivoted to swing in a horizontal plane toward 45 and from the folding-rollers B B.

In order to normally sustain the registering instrument in position to register the paper traversing said instrument, I provide the arm b with a supplemental arm f, extending 50 from the free end of the arm b and having connected to it an adjustable set-screw f', which constitutes the stop for arresting the swinging movement of the registering-arm e at its requisite registering position. To nor- 55 mally sustain the registering-arm e in said position, a suitable spring f² is arranged to hold the arm e in contact with the set-screw f'.

To allow the spring f² to be adjusted in its tension, I prefer to attach it to a collar g, 60 which is adjustably clamped on a hub g' on the extension of the arm b by means of a set-screw g², as more clearly shown in Fig. 4 of the drawings.

To the lower or free end of the registering- 65 arm e is attached the registering point or tongue e² for entering into the slit made in the paper for that purpose. Beneath this

registering-point is arranged a friction-pad h, preferably composed of leather. This pad is disposed with its top even or approximately 70 even with the plane of the tapes a a and is rigidly mounted on a plate h', secured to a slide h², which is supported in a longitudinal guide i, arranged parallel with the tapes a a. Said guide is secured at one end to the frame A and at its opposite end to a stationary cross-bar i' and is adjustable laterally thereon to harmonize the position of the guide with the lateral adjustment of the arm b, which carries the registering instrument. 80

The front stop D is carried at proper intervals to and from its paper-arresting position preferably by mechanisms similar to those shown in my Letters Patent No. 567,564, dated September 8, 1896, and consists of a 85 rock-shaft G, receiving intermittent motion from a lever G', attached thereto and actuated by a rotary cam H. An arm I, depending from said shaft and fastened thereto, is connected at its lower end to the outer end of a 90 horizontal longitudinal plate I', which is supported at its inner end upon a roller R, as shown in Fig. 2 of the drawings.

Through a nut N, fastened to the bar I', passes a screw O, which also passes through a nut D', secured to the front stop D, which rides on the bar I'. To the outer end of the screw is fastened a worm-gear P, secured to a horizontal shaft k, which extends across the machine and is journaled in arms h', projecting from the nuts N of the two screws O, which adjustably sustain the front stop D on the two bars I'. (Shown in Fig. 1 of the drawings.) A hand-wheel L or other suitable device is attached to the end of the shaft k for 105 turning the same, and thereby turning the screw O to adjust the front stop to its required position on its supporting-bars I', according to the size of the sheets of paper fed to the machine. 110

The registering point or tongue e' projects from the arm e rearward or to the paper-receiving end of the machine, and back of said point or tongue and in proximity thereto is the bridge l, which serves to open the slit in 115 the paper and facilitates the entrance of the point or tongue into said slit. This bridge is preferably formed of a thin metal plate which is adjustably secured to the guide i by means of a downward side extension l' of the bridge, 120 fastened to a block p, which is provided with a dovetail tongue p', inserted into a correspondingly-shaped longitudinal groove s in the side of the guide i, as shown in Fig. 7 of the drawings. By means of a spring t, interposed between the tongue p' and inner face 125 of the groove s, the block p, with the bridge l secured thereto, is held in its desired position. The described connection of the block p to the guide i permits the bridge to be adjusted in its position in relation to the registering point or tongue e'. 130

Each of the two slides h², which carry the pads h, is adjustably connected to the front

stop D by a screw n , projecting from a plate o , fastened to the under side of the slide. Said screw passes through a longitudinal slot o' in the slide h^2 and through a plate n' , mounted on top of the slide and provided with an upward-projecting tongue t , which engages a notch in the under side of the front stop D and is thus interlocked therewith, so as to cause the slide h^2 to move in unison with the front stop.

The operation of my invention is as follows: The paper is carried into the machine by the tapes $a a$ in the usual manner. In the meantime the registering instruments are elevated to allow the paper to freely pass under them, and the front stop is in its rear-most position to arrest the movement of the paper in time to place it in position to be folded. As soon as the paper has been arrested by the front stop the registering-arms $b b$ descend and cause the registering points or tongues e^2 to press the paper down upon the pads $h h$, so as to produce a frictional hold thereon. Then the front stop D moves forward and draws along with it the aforesaid pads, which by their frictional hold upon the paper carry said paper forward, and in this movement the points or tongues e^2 enter the slits in the paper, and in passing under the paper the vertical shanks e^3 of said points are brought in contact with the rear edges of the slits, and thereby arrest the movement of the paper. The points e^2 , with their shanks e^3 , are formed of very thin sheet metal, so that when the edges of the slits come in contact with the shanks e^3 , as aforesaid, the entire bottoms of the points e^2 are removed from the top of the paper, and thus relieves the paper from the downward pressure of said points and from the forward propelling force of the pads, and therefore obviates excessive straining the slitted portion of the paper, which is then left in its registering position. The blade C then tucks the paper into the bite of the folding-rollers, and in this operation the registering-arms e yield laterally to the draft of the paper and allow the same to pass through the folding-rollers without danger of causing the registering points or tongues to tear the paper or throwing it out of register.

It will be observed that by supporting the registering instruments by means of the pivots formed on the screws d^2 , which pass through the screw-threaded eyes d' in the supporting-bracket and can be turned to raise or lower the intervening hub e' of the registering instrument, said instrument can be adjusted to bear with the desired force upon the paper to be registered.

The registering-point e^2 I prefer to provide with a heel e^4 , to more effectually guard against the tearing of the paper during its lateral movement from the tapes.

65 What I claim as my invention is—

1. In combination with paper-delivering tapes and means for removing the delivered

paper laterally from said tapes, an instrument sustained yieldingly toward the aforesaid paper-removing means, a stop arresting the movement of said instrument in position to register the paper delivered by the tapes, and means for yieldingly holding the instrument in contact with said stop.

2. In combination with paper-delivering tapes and paper-folding rollers parallel with said tapes, a supporting-bracket over the tapes, an arm pivoted to said bracket to swing in a horizontal plane toward and from the folding-rollers and provided with means for engaging and registering the paper, a stop on said bracket arresting the movement of said arm at its registering position, and a spring holding said arm in contact with the aforesaid stop.

3. In combination with paper-delivering tapes and means for removing the delivered paper laterally from said tapes, a bracket over the tapes and provided with pivots disposed one above the other, an arm sustained by and between said pivots and provided with means for engaging a slit or perforation in the paper, a stop on said bracket arresting the swinging movement of said pivoted arm in position to register the paper, and a spring holding said arm in contact with the stop as set forth.

4. In combination with paper-folding rollers and paper-delivering tapes disposed parallel with said rollers, a registering instrument comprising a supporting-arm provided with two screw-threaded eyes disposed one above the other and axially in line, vertically-adjustable screws passing through said eyes and provided with pivot-points on their adjacent ends, a hub pivoted on said screws, a registering-arm extending from said hub toward the plane of the delivered paper, a stop on the aforesaid supporting-arm arresting the swinging movement of the registering-arm at its registering position, and a spring attached to the said supporting-arm and yieldingly holding the registering-arm in contact with the aforesaid stop as set forth.

5. An automatic point-feed registering instrument consisting of a supporting-arm adjustable in length, a registering-arm pivoted to said supporting-arm and vertically adjustable thereon, a stop on the supporting-arm limiting the swinging movement of the registering-arm and means for yieldingly holding the registering-arm in contact with said stop as set forth.

6. In combination with paper-delivering tapes, a rock-shaft over said tapes, an arm receiving oscillatory motion from said shaft and a registering-arm pivoted to said oscillatory arm as set forth.

7. On a paper-folding machine having the paper-delivering tapes parallel with the paper-folding rollers, the combination of a rock-shaft over said tapes, an arm receiving oscillatory motion from said shaft, a registering-arm pivoted to said oscillatory arm to swing to-

ward the folding-rollers and normally in position to register the paper delivered upon the aforesaid tapes, a stop sustaining the oscillatory arm in its normal position and a 5 spring yieldingly retaining said arm in contact with the stop as set forth.

8. In combination with paper-folding rollers, paper-delivering tapes parallel with said rollers, and alternately advancing and receding front stop, pads at opposite sides of the folding-rollers and in a plane even with that of the aforesaid tapes and connected to the aforesaid front stop to move therewith, a rock-shaft disposed transversely over the tapes, 10 rock-arms extending from said shaft, registering-arms connected to said rock-arms yieldingly toward the folding-rollers, and disposed over the aforesaid pads, stops on the rock-arms arresting the swinging of the registering-arms at their registering positions, and springs connected to the oscillatory arms and yieldingly holding the registering-arms in contact with the aforesaid stops as set forth.

9. In combination with paper-folding rollers and paper-delivering tapes parallel with said rollers, pads at opposite sides of the folding-rollers and in the same plane with the tapes, registering-arms over the pads and supported yieldingly toward the folding-rollers, 25 registering-points attached to said arms, and bridges facing said registering-points to open the slits in the paper preparatory to the entering of the registering-points as set forth.

10. In combination with paper-folding rollers, paper-delivering tapes parallel with said rollers, and an alternately advancing and receding front stop, pads at opposite sides of the folding-rollers and supported in the same plane with the aforesaid tapes, slides connecting said pads to the front stop, registering-arms over the pads and supported yieldingly toward the folding-rollers, registering- 30

points attached to said arms, and bridges facing said registering-points to open the slits in the paper for the entering of the register- 45 ing-points as set forth.

11. In combination with the registering-arm provided with a registering-point and an alternately advancing and receding front stop temporarily arresting the movement of the 50 paper under said registering-arm, a stationary guide disposed parallel with the tapes, a slide in said guide provided with a longitudinal slot, a plate mounted on said slide and connected to the front stop, a bolt passing 55 through the slot of the slide and adjustably securing the aforesaid plate to said slide, a pad attached to the opposite end of the slide and disposed under the aforesaid registering-arm and a slit-opening bridge attached to the 60 aforesaid guide as set forth.

12. In combination with the paper-delivering tapes, and adjustable front stop, a rock-shaft transversely over said tapes, a longitudinally-adjustable rock-arm extending from 65 said rock-shaft, a vertically-adjustable registering-arm carried on said rock-arm and provided with a registering-point, a stationary longitudinal guide, a slide in said guide and provided with a longitudinal slot in the 70 end portion under the front stop, a plate mounted on said slide and connected to the front stop, a bolt passing through the slot of the slide and adjustably securing the aforesaid plate to the slide, a pad attached to the 75 opposite end of the slide and disposed under the registering-arm and a slit-opening bridge connected to the aforesaid guide adjustably lengthwise thereof as set forth.

TALBOT C. DEXTER. [L. S.]
